Application December 30, 1954, Serial No. 478,663

3 Claims. (Cl. 235—132)

This invention relates to indexing a card stacker in a tabulating card printing machine and more particularly to counting the cards as they are fed into the card stacker.

Tabulating cards are stacked at the completion of a printing of the cards. It has been found that an ultimate package of 2,000 cards is a desirable standard size package of completed cards. According to one method of stacking printed cards, the cards are divided during the stacking operation and then collected into a single bundle of 2,000 cards. The division of the cards, however, must provide groups which can be assembled into 2,000 cards without counting. Accordingly, it is necessary that the cards be counted at the stacking operation and further that the stacked groups consist of a card count which will permit an easy union to a 2,000 card package. This applies equally to the composition of any card package in a standard number of cards from stacked groups.

The grouping of cards in this manner is best accomplished by counting the cards immediately prior to or as they are stacked. The counting must be combined with indexing of the card stacker to provide the card group formation operation which results in the automatic preparation of card groups which are combinable into a package of a standard number.

It is an object of this invention to provide a device for the placement of cards in stacks having predetermined amounts of cards combinable into a package of cards of a given number.

It is another object of this invention to count tabulating cards stacked from a card printing machine successively in groups of a different number, with a given number of these groups combinable into a package of a given number.

It is a further object of this invention to provide a means and a method for counting tabulating cards printed on a card press and to provide stacks of said counted cards which complement each other in numbers, so that any three successive stacks combine to form a package of 2,000 cards.

It is a still further object of this invention to provide in a tabulating card press apparatus, a combination of means for counting and stacking completed cards and indexing a stacker with a given number of groups of cards combinable to produce a package of a standard number of cards.

These and other objects of this invention will become more apparent upon consideration of the following description taken together with the accompanying drawings, in which:

Figure 1 is a wiring diagram for the card counting and card stacker indexing means of the device of this invention;

Fig. 2 is a chart of the relationship between the card sensing switch of the counting means and the pulse-producing cams;

Fig. 3 is a wiring diagram of the circuit for the stacker indexing solenoid;

Fig. 4 is a side elevation of a portion of a card conveyor drum and a card stacker;

Fig. 5 is a perspective view of a counter unit;

Fig. 6 is a partial bottom view of the card sensing and counting mechanism;

Fig. 7 is a plan view of the stacker table and associated parts;

Fig. 8 is a plan view of the stacker table actuating and stopping mechanism portion of the card conveyer drum;

Fig. 9 is an enlarged plan view of the card catcher and stacker table taken from the same side as Fig. 7;

Fig. 10 is a detailed front view of the clutch engaging mechanism for the stacker table actuating means and card catcher; and

Fig. 11 is a side view of the stack movement cut-off switch and rod for permitting clutch engagement.

In the embodiment of this invention described herein, the card stacking is related to making up units of 2,000 cards from any three stacks of cards. The card stacks

are counted and accumulated on a table and moved by the indexing of the table. This is accomplished by making up on the stacker table of stacks of 667, 667, 666, 667, 667 and 666 cards in sequential repetition. The stacking of cards in these groups in a tabulating card

printing machine depends on a control means for indexing a table on which cards are stacked after counting. The control means of this embodiment may be incorporated in a modification of the Tabulating Card Printing Machine, described in United States Letters Patent

No. 2,181,935, issued December 5, 1939, to Fred M. Carroll. The control means provides a stack of cards in the amount of 667, a second stack in the amount of 667 cards and a third stack in the amount of 666 cards.

The amounts of the cards is determined by the control means which is responsive to the completion of a first circuit at a predetermined count of 667 cards. On completion of the first count, a second circuit is set up for a second predetermined count of 667 cards. A third circuit is set up at the second count. The third circuit is completed at a third predetermined count of 666 cards.

At the completion of each count the counted cards which have been stacked are moved by the indexing of a stacker table on which the counted cards are piled.

Fig. 1 shows the wiring diagram for the control means of the described embodiment. In this control means, a group of relays 11, 12, 13, 14', 15 and 15' control sets of contacts to provide a means responsive to the stacked cards. The switches prefixed by 15' are controlled by relay 15.

The control means of the embodiment has three emitters 16, 17 and 18 for counting the cards. The emitter 16 counts units, the emitter 17 counts tens and the emitter 18 counts hundreds. Each of the emitters 16, 17 and 18 are provided with a ratchet relay 19 and an advance relay 20.

The respective relays 19 and 20 operate a wiper arm 21 in emitter 16, a wiper arm 22 in emitter 17, and a wiper arm 23 in emitter 18. The respective wiper arms 21, 22 and 23 are moved across a series of ten contacts 24 for each of the respective emitters 16, 17 and 18 and contact bars 26, 27 and 28 for the respective emitters. A power line 25 supplies the necessary electric current.

Timing pulses are produced in the control means by three cams 29, 30 and 31, which are driven in synchronism with the card holding wheel described in detail below. The cams 29, 30 and 31 which rotate once for each card delivered to the stacker actuate respective contacts 32, 33 and 34. The cam 29 through the contacts 32 connects the power line 25 to the add relays 20 through a conductor 35. The cam 30 connects power line 25 to the ratchet relays 19 through a combination of relay and cam actuated contacts which control the conditioning of add relay-ratchet relay control of the respective wiper

arms 21, 22 and 23. The cam 31 connects the power line 25 directly to the contact bar 26 through contacts 34 and conductor 36.

The relays 14 and 14' control the cutting off of the stacking of cards and the indexing of the stacker table when the various predetermined counts of 667 and 666 have been completed. The wiring of the control means accordingly provides for the energization of the relays 14 and 14' when the predetermined counts have been achieved. The energization of relays 14 and 14' at the opportune time in card counting is effected through sets of contacts associated with the emitter contacts 24 and a set of three contacts connected in parallel at the relays 14 and 14'. Three contacts 12-1, 12-2 and 12-3 are connected to the respective 24-0 contacts of emitters 16, 17 and 18, and connect the emitters 16, 17 and 18 together and connect to relay 13 through conductors 40 and to the relay 14 through a conductor 37 and an intervening contact 12-6. The contacts 12-1, 12-2, 12-3 and 12-6 are controlled by relay 12, as well as contacts 12-4 and 12-5.

Similarly, relays 11 and 13 control contacts 11-1, 11-2, 11-3, 11-4, 11-5 and 11-6 and 13-1, 13-2, 13-3, 13-4, 13-5 and 13-6, respectively. Contacts 11-1 are connected to contact 24-4 of emitter 16, contacts 11-2 are connected to contact 24-3 of emitter 17 and contacts 11-3 are connected to contact 24-3 of emitter 18 and also to relay 12 through conductor 38 and to relay 14 through contacts 11-6 and conductor 39. Contacts 13-1, 13-2 and 13-3 connect to contacts 24-7, 24-6 and 24-6 of emitters 16, 17 and 18 respectively. Contacts 13-3 are connected to relay 11 through conductor 41 and relay 14 through contacts 13-6 and conductor 42. It will be noted that contacts 13-6, 11-6 and 12-6 are connected together and to relay 14 by a conductor 104. Thus, the energization of the relay 14 is controlled by the positioning of the wiper arms 21, 22 and 23 and the closing of the respective sets of contacts 11-1, 11-2, 11-3 and 12-1, 12-2, 12-3 and 13-1, 13-2, 13-3 and 11-6, 12-6 and 13-6 by their respective relays 11, 12 and 13.

The relays 11-15 are provided with hold circuits which connect them to the power line 25 through respective contacts. Relay 11 has a hold circuit of conductor 43, contacts 12-5 and 11-4. Relay 12 has a hold circuit conductor 44 and contacts 13-5, 12-4 and 15-6. Relay 13 has a hold circuit of conductor 45 and contacts 11-5, 13-4 and contacts 46. Relay 15' has a hold circuit of conductor 47, contacts 15-8 and 46. Relay 14 has a hold circuit of conductor 48, contacts 14-1 and micro-switch 49.

Fig. 2 shows the cycle of cams 29, 30 and 31. A complete cycle of the three synchronized cams is 360°. Each cam closes its respective contacts for a 90° phase of the cycle and the angular rotation between phases is 30°. The timing of the cam action is related to the sensing and counting of the cards so that during the closing of contacts 33 by cam 30 only one card will be in contact with the sensing finger as described more fully below. This provides the check in the device for a hiatus in the card feed or a missing card.

Cams 29, 30 and 31 are adjusted to operate their respective contacts sequentially. Cam 30 closes contacts 33 first to set up the counting mechanism. Cam 29 closes contacts 32 to add the count, and cam 31 closes contacts 34 to index the stacker when the desired number is reached. The cams 29, 30 and 31 are geared to the driving mechanism.

Fig. 4 shows a card conveyer wheel 50 which carries the tabulating cards in the embodiment of this invention. This card conveyer wheel 50 is substantially the same as the conveyer wheel shown and described in the above-noted patent. Reference is hereby made to the disclosure of the device for conveying and stacking tabulating cards in said patent. The conveyer wheel 50 is shown deposit-

ing tabulating cards 51 onto a stacker table 52. The cards are held in an upright stack 53 by a plate 54 and guide bars 55.

The stacker table 52 has associated with the plate 54 and guide bars 55, forming a stacker pocket 72, a card catcher 56 which consists of a bifurcated plate. The relationship between the stacker table 52 and the card catcher 56 and the card stacks 53 is shown in Fig. 7. The mechanism for actuating, positioning and resetting the card catcher 56 is shown in more complete detail in Fig. 10, which is also shown in Fig. 7, while showing the adaptation of this invention to the disclosure of the above-noted patent.

The stacker table 52 indexing means 57 is shown in Fig. 8. The stacker table 52 is rotated by an arm 58 connected by a link 59 to a plate 60. A ratchet disk 61 is mounted on a hub 62 of the table 52 and is engaged by a pawl 63. The pawl 63 is held in the disk 61 by a spring 64. As described in the above-noted patent, the table 52 is rotated in angular increments by the indexing means 57 as driven by a shaft 65, attached to the arm 58.

Concomitant with the indexing of table 52 at the completion of a predetermined count is the cutting-off of further deposit of cards in the stack of the predetermined count. This cut-off is accomplished by the actuation of the card catcher 56 from the position shown in Fig. 9, to intercept the cards 51. The initiation of the card catcher movement is instituted by the energization of a solenoid 66 at the completion of the predetermined count by the energization of relay 14, as will be explained in greater detail below.

The solenoid 66 is provided with a core 67 which carries a detent 68. The detent 68 engages a rod 69 which is pivotally mounted on the shoulder of the card catcher 56 by a pin 70. The rod 69 is under the compression of spring 71 which turns the card catcher 56 by the leverage between the pin 70 and the rotatable mounting of the card catcher 56. The card catcher 56 is quickly driven into the stacker pocket 72 cutting off the cards 51 during the indexing operation. The upper end of the rod 69 is formed with a bullet-shaped nose 73 which supports a lever 74 as shown in Fig. 10. The horizontal movement of the rod 69 in an axial direction, as seen in Fig. 9, causes the nose 73 to allow the lever 74 to drop as seen in Fig. 10.

The fall of the lever 74 has a double action. As shown in Fig. 11, the lever 74 engages a finger 86 of the micro-switch 49 as it falls. This deenergizes the hold circuit of the relay 14 and opens the contacts 14-2 and 14-3 of the solenoid 66 circuit causing the solenoid 66 to de-energize and release the detent 68 for engagement with rod 69 when the rod 69 is subsequently returned to latching position. The rod 69 and the card catcher 56 with it, however, are held in extended position by the expansion of spring 71.

The other action of the fall of lever 74 is the product of a turning motion effected in a shaft 75 on which the lever 74 is mounted at its end opposite from the nose 73. As shown in Fig. 10, a hub 76 is provided with slots 77 to act as a continuously rotating clutch. As shown in the plan view of Fig. 9, a dog 78 is engageable in one of the slots 77 under the urging of a spring 79. The dog 78 is pivotally mounted on a driven disk 84. The disk 84 is suitably mounted on a shaft 80, also as described in the above-noted patent. The shaft 80 carries a circular eccentric cam 81 and horn-shaped cam 82 mounted thereon to be rotatable with said hub 76 upon engagement of said dog 78 in a slot 77. The rotation of the shaft 75 disengages a small lever 83 from a restraining projection on the dog 78 and permits the dog 78 to engage in a slot 77.

The cam 81 actuates the table indexing means 57 by means of a cam follower, not shown, mounted on the shaft 65 in accordance with the disclosure in the above-

noted patent. The cam 82 rotates with the shaft 80 and engages a hook-shaped projection 85 which extends from the shoulder of the card catcher 56 counter to the main body. The engagement of the projection 85 by the cam 82 causes a opposite movement of the card catcher 56 which withdraws it from the stacker pocket 72 and forcing the rod 69 against the action of the spring 71 relatches the detent 68 in the rod 69. The axial repositioning of the rod 69 moves the bullet-shaped nose 73 against the lever 74 rotating the lever 74 in a clockwise direction as seen in Fig. 10. The lever 74 does not disengage from the nose 73 when the rod 69 moves axially. Consequently, when the rod 69 and nose 73 are moved to the latched up position shown in Fig. 9, the lever 74 simply cams on the incline surface of the nose 73 and the lever 74 is smoothly raised, rotating the shaft 75 and moving the small lever 83 under the dog 78 projection to disengage the dog 78 from the hub 76. The cams 81 and 82 become stationary and the stacker table 52 indexing cycle is completed with an empty stacker pocket 72 positioned to receive a new stack 53 of cards 51.

In Fig. 5 a perspective view shows a means for providing counting in an emitter by the action of ratchet and advance relays, such as in this invention. The mechanism of Fig. 5 is an example of the emitter ratchet advance relays assembly of the units, tens and hundreds counters in the control means. The emitter 16 is shown as an example with the ratchet relay 19 and advance relay 20 joined by beam 87 sliding in mortises in supporting members 88. A plate 89 pivotally mounted at the middle of the beam 87 is connected to an emitter shaft 90 which carries a ratchet wheel 91 at its lower end, a "9" cam 92 and a "0" cam 93 adjacent its middle and the wiper arm 21 at the upper end. The wiper arm 21 is surrounded by the contacts 24-0 to 24-9.

The cams 92 and 93 turning with the shaft 90 open and close contacts 101 and 106 respectively as shown in Fig. 1. The contacts 106 are closed except at "0" and the contacts 101 are closed at "9" only. The tens and hundreds are isolated and can be pulsed only through the unit counter. This pulsing occurs when emitter 16 is on "9" and wiper arm 21 is on 24-9 as shown in Fig. 5. The contacts 101 are closed. Contacts 15-4 normally open are closed since 15 is energized. Then the tens ratchet relay 19 is energized, cocking the tens counter and on the next card the tens advance relay 20 associated with emitter 17 indexes the ten emitter 17 on a pulse from contacts 32.

In counting in the control means the emitter 16 is conditioned by energization of the ratchet relay 19 to draw the beam 87 to the left as seen in Fig. 5 and to lock a pawl 94 on the ratchet wheel 91.

The subsequent energization of the advance relay 20 will draw the beam 87 to the right, as seen in Fig. 5 and through the engagement of the pawl 94 in the ratchet wheel 91 cause an angular movement of the shaft 90 moving the wiper arm 21 from one of the contacts, such as 24-9 to the next higher, such as 24-0. The current is provided to the wiper arm 21 through a slip ring 95. Thus, the emitter can be advanced to provide a circuit through any one of the contacts 24-0 to 24-9 in the emitter 16. The emitter 16 has been described for the purpose of illustration.

The predetermined count of cards is performed by the apparatus of this invention through the emitters 16, 17 and 18. The cams 29, 30 and 31 provide the timed pulses which energize the counting system of the emitters 16, 17 and 18. The cams 29, 30 and 31 are driven in synchronism with the card conveyer wheel 50 and complete one 360° revolution for each card 51 delivered to the stacker pocket 72. The cam 30 is timed to close contacts 33 each time a card 51 is in position to drop into the stacker pocket 72. The card at the same time closes contacts 96 through a finger 97. If there is no

card 51, no current is passed for a count since the contacts 96 are not closed. In operation, when counting continuous cards, the contacts 96 are kept continuously closed. The finger 97 is always in contact with at least one of the cards 51. The finger 97, as shown in Fig. 6, is in contact with two cards during a part of the cycle. This is illustrated further in Fig. 2. During the phase of the closing of contacts 33 by cam 30, the finger 97 is in contact with only one card. Thus, if a card is missing, it is during this phase of the cycle that no contact can be made at contacts 96. When the contacts 96 open, the circuit is interrupted and there is no count during the respective cycle of the cams 29, 30 and 31. The operation of the control means of this invention is initiated by indexing the wiper arms 21, 22 and 23 to their respective 24-0 contacts. To move the wiper arms 21, 22 and 23 to "0", the relay 12 is energized by closure of contacts 13-5, 12-4 and 15-6. This closes contacts 12-1, 12-2 and 12-3. The rest of the relays 11, 13, 14 and 15 are de-energized. Thus, contacts 11-1, 11-2, and 11-3 are open, as well as contacts 13-1, 13-2 and 13-3. The contacts 12-6 are also closed while contacts 11-6 and 13-6 are open. Contacts 15-3, 15-2, 15-1a and 15-7 are closed. Consequently, pulses are transmitted to the relays from cam 30 and contacts 33 through contacts 15-7, 15-1a, 15-2, 15-3 to contacts 105, 98 and 99, associated with emitters 16, 17 and 18, respectively. Each pulse through the contacts 33 causes all of the ratchet relays 19 to condition the respective emitters, as described above in connection with Fig. 5. If the wiper arms are not at the 24-0 contacts for their respective emitter, the closing of cam 31 will have no effect upon the counting circuit. The ratchets are all conditioned and the next closing of the contacts 32 by the cam 29 pulses the advance relays 20 and operates the ratchet 91 and pawl 94, as described above in connection with Fig. 5. Thus, the wiper arms 21, 22 and 23 are rapidly moved around to the 24-0 position. When they all reach 24-0, a current from contacts 34, upon closing cam 31, will be transmitted to relay 14. Relay 14 controls contacts 14-1, 14-2 and 14-3. The closing of the contacts 14-2 and 14-3 thus causes an energization of the solenoid 66 causing an indexing of the table and signifying that the control means is in condition for counting. Each of the relays 11, 12 and 13 operates substantially the same.

It is understood that it is the purpose of this invention to provide a means for counting cards into three stacks, two composed of 667 cards and the other composed of 666 cards. This device accomplishes this purpose in the following manner: to count to 667 with the control means, the relay 13 is energized. This closes contacts 13-1, 13-2, 13-3, 13-4 and 13-6 and opens contacts 13-5 in the hold circuit for relay 12 which consequently de-energizes relay 12.

At the inception of the first stack 53 count, relays 14 and 14' are momentarily energized to cause an indexing of the stacker table 52 by the operation of the indexing means 57, as shown in Figs. 8 and 9. As explained above, the rapid opening micro-switch 49 in the indexing operation causes the indexing operation to be completed very quickly. As soon as the card catcher 56 is returned to the position of Fig. 9, by the operation described above, the control means is prepared for the count. In this condition, relays 11 and 12 are de-energized, relays 13 and 15 are energized, and relay 14 has been energized and is again de-energized. Contacts 12-1, 12-2, 12-3, 11-1, 11-2, 11-3, 15-1a, 15-2, 15-3 and 15-7 are open and also contacts 15-6, 12-4 and 13-5 in the hold circuit are open for relay 12. Contacts 11-4 in the hold circuit are open for relay 11. It is to be noted that contacts 13-6 are closed as well as contacts 13-1, 13-2 and 13-3.

In the circuit associated with the relays 19 and 20, the contacts 15-4 and 15-5 are closed. Each time the cam

30 closes its contact and a card causes the finger 97 to close the contacts 96, a pulse is transmitted to ratchet relay 19 for emitter 16 through the contacts 15-1b. As contacts 15-2 and 15-3 are open, no pulse is transmitted to the emitters 17 and 18. After the ratchet wheel 91 of emitter 16 is conditioned with the pawl 94, as described above, the closing of the contacts 32 by the cam 29 advances the wiper arm 21 in the same manner as described above in connection with Fig. 5. This advance continues until the wiper arm 21 reaches the contacts 24-9. The relay 19 for the emitter 17 is then conditioned through the action of the cam 92 of the units counter, which closes contacts 101 and transmits a pulse through contacts 15-4 to the relay 19 for the tens counter. For every 10 counts of the emitter 16 by the ratchet and advance stepwise method just described, the tens counter will be advanced one contact. For every 10 advances of the wiper arm 22 of the emitter 17, the emitter 18 will be advanced one contact by the action of a cam 102 and contacts 103 in the same manner as described above in connection with the units and tens counters.

This indexing and counting continues throughout the counting of the first 667 cards. It will be seen that the contacts 13-1, 13-2 and 13-3 are closed for the first predetermined count and connected to contacts 24-7 in emitter 16, contacts 24-6 in emitter 17 and contacts 24-6 in emitter 18. Thus, when the respective wiper arms 21, 22 and 23 all reach the respective contacts 24-7, 24-6 and 24-6, the next pulse through conductor 36 from contacts 34 on closure by cam 31 will run through the emitters 16, 17 and 18 to conductor 42, closed contacts 13-6 and a common conductor 104. Thus, the relay 14 is energized setting into operation the card cut off by the card catcher 56 and the indexing of the stacker table 52. The cut off and indexing takes place at this point in the count as the count indicates the first predetermined card stack of 667 has been achieved.

In the next counting phase, the relay 11 is energized and the relays 12 and 13 are de-energized. Contacts 11-1, 11-2, 11-3, 11-6, 11-4 and 11-5 are closed, while contacts 13-1, 13-2, 13-3, 13-4 and 13-6 have been opened. Contacts 12-1, 12-2, 12-3 and 12-6 remain open in this phase as do contacts 15-1a, 15-2 and 15-3. Contacts 12-5 remain closed to provide a hold circuit for relay 11 through conductor 43. With the various contacts thus disposed, the pulse from the contacts 34, through the conductors 36, in the respective contact bars 26, 27 and 28 will be conducted to the index initiating relay 14 when the wiper arms 21, 22 and 23 reach their respective contacts 24-4, 24-3 and 24-3. The control means will count another 667 cards in this second predetermined count in reaching these emitter contacts. Thus, another stack 53 of 667 cards will be piled in the stacker pocket 72 of the stacker table 52 before the indexing operation is repeated. With the counting of the 667th card, the card catcher 56 will once again swing into action under the operation of the means described above. This will give a total of 1334 cards counted in two card stacks 53. To reach the desired total of an even 2,000 cards, the control means next counts 666 cards for indexing. In the third predetermined count, the relay 12 is energized closing contacts 12-1, 12-2, 12-3, 12-6 and 12-4 and leaving contacts 13-5 closed to provide a hold circuit relay 12 for conductor 44. The contacts 11-4 are open, as are contacts 13-4, to open the hold circuits for the relays 11 and 13. The wiper arms 21, 22 and 23 of the respective emitters 16, 17 and 18 are advanced by the combined action of the respective ratchet relays 19 and advance relays 20, as described above in connection with the previous predetermined counts. The wiper arms 21, 22 and 23 will move through 666 counts in advancing from the contacts 24-4, 24-3 and 24-3, respectively, at the close of the second predetermined count to the three 24-0 contacts at the close of the third predetermined count. At the close of the third predetermined count, the pulse from the

contacts 34 through conductor 36, the contacts 12-1, 12-2, 12-3, conductor 37 and contacts 12-6 to relay 14 completes the counting of 2,000 cards. The indexing operation is repeated with the activation of the indexing means 57 and the reciprocation of the card catcher 56.

Thus, the operation of the control means for providing three stacks of cards is completed. The three stacks of cards according to this invention, when added together, equal 2,000 cards. Upon continued operation of the conveyer wheel 50 and the deposit of cards 51 subject to the control means of this invention, additional stacks 53 will be prepared, each containing a predetermined count of cards 51. These stacks will be made up repetitively sequentially of 667, 667, 666, 667, 667 and 666 cards, etc. Thus, three sequential stacks of cards, added together, will equal 2,000 cards.

In the counting of the cards into groups of predetermined number, according to this invention, each count completion sets up the circuit for the next predetermined count; for example, the first 667 count with the relay 13 energized is set up by the contacts 12-1, 12-2 and 12-3 in the previous indexing to "0." The relay 13 is held energized by contacts 11-5, 13-4 and 46. The second 667 card count with the relay 11 energized is set up by the contacts 13-1, 13-2 and 13-3 of the previous count. The relay 11 is then held energized by contacts 11-4 and 12-5 and finally the 666 card count is set up by energization of relay 12 through contacts 11-1, 11-2 and 11-3 with the relay 12 held by contacts 12-4, 13-5 and 15-6.

This invention has been described as applied to obtaining a total of 2,000 cards in three stacks by repetitious sequential counting of the cards. It will be understood that this embodiment has been described for the purpose of illustrating the invention and that it may be modified to provide a different total count with different predetermined counts and other numbers of stacks containing different predetermined counts. Moreover, this variable counting device has been applied to one form of a card conveyer and depositor with a specific means for indexing and card catching. It will be readily understood that the counting device of this invention may be applied to other card printing and conveying machines and other means for indexing or removing the stacks of predetermined counts.

The invention thus provides a means for obtaining a given total count in subdivided groups. The sub-divided groups when combined together in accordance with their sequential formation invariably produce the desired total count. This count is obtained positively from the cards as deposited. Accordingly, it takes into consideration a missing card. It is a further advantage of this invention that a dumping switch is provided in the contacts 46. This permits a stack to be eliminated when it contains mutilated cards. It is a further advantage of this invention that when a stack is thus dumped, the control means contains the means for indexing to start a new group automatically at the proper orientation of the emitter wiper arms.

In view of these advantages and the possibility of modifications, as intended above, it is intended that this invention be limited only by the scope of the appended claims.

What is claimed is:

1. A card compiling device for stacking cards in groups of designated numbers totaling a specified number of cards, comprising a first cam, first contacts closed by said first cam, a second cam, second contacts closed by said second cam, a third cam, third contacts closed by said third cam, said first, second and third cams being arranged to close said respective contacts sequentially, a stacker table receiving tabulating cards, means for indexing said stacker table, means for intercepting said tabulating cards during said indexing, means for moving said interceptor, a cut-off solenoid energizable to actuate said indexing means and said interceptor moving means to produce card groups of designated numbers of cards, a master relay energizable

to energize said cut-off solenoid, a counter connected to said master relay to provide energizations therefor including a first emitter of the units order, a second emitter of the tens order, a third emitter of the hundreds order, an emitter arm in each of said first, second and third emitters, ten emitter contacts in each of said emitters engageable sequentially by said respective emitter arm, a first solenoid for each of said respective emitters, a second solenoid for each of said respective emitters, means pulsed by said first contact for energizing said first solenoids to condition means in said emitter for moving said respective emitter arm sequentially across the respective emitter contacts, means pulsed by said second contact for energizing said second solenoids to operate said conditioned means and move said respective emitter arm in sequential engagement with the respective emitter contacts, means for energizing said second solenoid of said units emitter with each rotation of said first, second and third cams, means for energizing said second solenoid of said tens emitter with each ten advances of said units emitter arm, means for energizing said second solenoid of said hundreds emitter with each ten advances of said tens emitter arm, three card-counting contacts connected each to individual emitter contacts in each of said emitters, three relays, one of the

card-closing contacts in each emitter operable by one of said relays, said relays being sequentially energizable, means for supplying energization pulses to said relays from said third contacts through said emitter contacts and said card-counting contacts, and means connecting one of said card-counting contacts in each of said emitters to said master relay for each of card groups.

2. In a device as claimed in claim 1, a card actuated switch in said first solenoid actuating means interrupting the counting operation of said device so that the absence of a card results in no count during the cycle of the first, second and third cams.

3. In a device as claimed in claim 1, a switch in the circuit of the master relay actuated by a mutilated card to energize said master relay.

UNITED STATES PATENT OFFICE
CERTIFICATE OF CORRECTION

Patent No. 2,827,237

March 18, 1958

Edward B. Erickson

It is hereby certified that error appears in the above numbered patent requiring correction and that the said Letters Patent should read as corrected below.

In the drawings, Sheets 1, 2, 3 and 4, line 2, and in the heading to the printed specification, line 3, for that part of the title of invention reading "OR ROTARY CARD PRESS", each occurrence, read -- FOR ROTARY CARD PRESS --; column 2, line 46, after "13," insert -- 14, --; column 5, line 16, for "smoothly" read -- smoothly --.

Signed and sealed this 12th day of August 1958.
